UNITED STATES PATENT OFFICE.

EZRA FLOYD AMES, OF PORTLAND, OREGON.

SAFE-DEPOSIT BOX.

Application filed October 29, 1927. Serial No. 229,690.

My invention relates to safe deposit boxes installed in vaults.

Since the space allotted to each box is restricted, the boxes are formed long and narrow and are fitted snugly into their respective compartments.

The individual doors with which each compartment is provided are relatively thick and the housing of the lock is fixed to the inside 10 of the door and extends into the compartment, necessitating that the compartment be constructed deep enough to allow the box to be inserted therein far enough back to clear the door when it is closed.

Because of this construction, when the door 15 of the compartment is opened, it is inconvenient and difficult to reach the box and withdraw it from its compartment with the hand, so that the attendant frequently has to 20 use a hook-like implement to aid him in the pulling out of the box.

Therefore, the principal object of my invention is to provide simple and efficient means to cause the projection of the safe deposit box beyond the front wall of the vault 25 simultaneously with the opening of the door of the compartment so that the safe-deposit box may be easily and conveniently grasped and withdrawn with the hand by its owner.

Another object of my invention is to provide simple and efficient means for accomplishing the above stated object which may be installed in large vaults at a relatively 30 low cost.

I attain my objects in the combination with a safe-deposit box and the door of its compartment of means adapted to cause the movement of the box out of its compartment to follow automatically with the opening of the 35 door of the compartment, so that the box will project outward of the front wall of the compartment when said door has been opened.

Said means is further adapted to return the box back in its compartment with the 40 closing of the door.

The foregoing and other incidental features, as well as the details of construction and operation of my invention are hereinafter 45 fully described with reference to the accompanying drawings:

Fig. 1 shows a fragmentary front elevation of a number of safe deposit box compartments, showing one of the doors half open, disclosing the safe deposit box therein, and 50 illustrates the operation of my invention, the door being shown in a transverse section;

Fig. 2 shows a section taken on the line 2—2 of Fig. 1, and illustrates the details of construction and relative arrangement of my invention when installed on a safe deposit box; 60

Fig. 3 shows a fragmentary enlarged section taken similarly to Fig. 2, except that the door is partly open and the safe deposit box is being moved outwardly;

Fig. 4 shows a section taken similarly to 65 Fig. 3, except that the safe deposit box has been moved to project beyond the front wall of the compartment;

Fig. 5 shows a section taken on the line 5—5 of Fig. 2, and illustrates further details 70 of construction;

Fig. 6 shows an enlarged fragmentary perspective view of the spring lever provided on the front of the safe deposit box;

Fig. 7 shows the spring arm provided on 75 the inside of the door of the compartment, which engages with the said lever;

Fig. 8 shows a diagrammatic plan section of a safe deposit box compartment and the box therein, and illustrates a modification of 80 my invention.

In Figs. 1 and 2 are shown the usual arrangement of a safe deposit box in its compartment.

The compartment *a* is commonly provided 85 with a door *b* hinged as at *c* and provided with a lock *d*. The safe deposit box *e* is inserted therein and the compartment is constructed deeper than the length of the box so that there is a relatively large space between 90 the front end of the box and the door, when the latter is closed.

The floor *a'* of the compartment is provided with a groove *f* flared at its open end, and the front end *g* of the box *e*, (Figs. 3, 4, and 6) is provided with a spring controlled lever *h* fixed on a shaft *j*, journaled in brackets *i* fastened on the said front of the box. The end of the shaft *j* adjacent the hinged portion of the door is provided with a crank 100 end *j'* and the lever *h* is provided with a centrally arranged hole *h'*.

Fastened to the inside of the door adjacent the hinge is provided a U-shaped spring arm *k*, (Figs. 5 and 6) pivoted on a bracket *l*. The ends *k'* and *k''* of the arm *k* are provided with downwardly extending lugs *m* and *n*, respectively, and the arm *k* is arranged so that the lugs *m* and *n* will register respectively with the hole *h'* and the groove *f* in the floor of 110 the compartment.

By this construction and arrangement when

the box *e* is placed in its compartment and the door closed, the lugs *m* and *n* on the arm *k* will be engaged with the hole *h'* and the groove *f*, respectively, the latter serving as a guide for 5 the arm *k*.

When the door is opened, the arm *k* will draw the box *e* outward with it until the 10 crank end *j'* strikes against a projecting part *p* of the door hinge, which is part of the usual construction of hinges of this type, which moves downward, moving the spring lever *h* downward also and releasing the lug *m* from the hole *h'*.

Thus the door, as it is opened, moves the box 15 out until it projects beyond the front wall of the compartment, so that the box may be easily grasped by the hand, and the door being disengaged therefrom may be opened wide, and the box removed easily and conveniently.

20 When the box *e* is replaced in its compartment and the door closed, the projection *p* on the hinge will strike against the crank end *j'* and rotate the said crank end and move the spring lever *h* downward so that the lug *m* 25 may pass over the said lever and engage in the hole *h'*, being guided therein by the lug *n* in the groove *f*. Simultaneously, the projection *p* will push the box *e* back into the compartment, assisted by the arm *k* after it has 30 engaged the lever *h*. The box *e* is again in position to be projected the next time the door is opened.

Referring to Fig. 8, I have shown a modification of my invention in which a coil spring 35 *q* is fixed to the back wall of the compartment, and an arm *s*, provided with a roller *t* is fixed on the inside of the door, and by this construction when the box *u* is placed in its compartment, the door closed, the roller *t* will push 40 the box back against the spring *q* and compress it.

When the door is opened the arm *s* will swing away from the box *u* and permit the spring *q*, which has been compressed, to expand and move the box forward until it projects beyond the front wall of the compartment and may be easily grasped by the hand.

I claim:

1. In combination with a compartment for 50 housing a safe-deposit box, the door of the compartment and the box therein contained, cooperating means carried by the inner face of the door and the front end of the box, respectively, adapted to connect the said front 55 end of the box with the door, whereby to cause the opening movement of the door to project the said box from its compartment, said connecting means being further adapted to release automatically themselves when the door 60 is swung fully open.

2. In combination with a compartment for

65 housing a safe deposit box, the door of the compartment and the box therein contained, cooperating means carried by the inner face of the door and the front end of the box, respectively, adapted to connect the said front end of the box with the door, whereby to cause the opening movement of the door to project the said box from its compartment, said connecting means being further adapted to release automatically themselves when the said door is swung fully open, and to effect the 70 return of the box back in its said compartment with the closing of the door.

3. In combination with a compartment for 75 housing a safe-deposit box, the door of the compartment and the box therein contained, cooperating means carried by the inner face of the door and the front end of the box, respectively, adapted to connect the said front end of the box with the door, whereby to cause the opening movement of the door to project the said box from its compartment, said connecting means being further adapted to release automatically themselves when the said door is swung fully open, and to effect the 80 re-engagement of said cooperating means, and the return of the box back in its said compartment with the closing of the door.

4. In combination with a compartment 90 housing a safe deposit box, the door of the said compartment, the hinge of the door, and the box contained in the said compartment, a spring controlled arm mounted on the inner face of said door, and a spring controlled 95 lever mounted on the front end of said box, engaging means provided on said arm and said lever, whereby the said box will be projected and returned as the said door is opened and closed.

5. In combination with a compartment 100 housing a safe deposit box, the door of the said compartment, the hinge of the door, and the box contained in the said compartment, a U-shaped spring controlled arm mounted on 105 the inner face of said door, the ends of said arm being provided with lugs, a crank-shaft transversely journaled on the front end of said box, a spring controlled lever fixed on said crank shaft, adapted to be engaged by one of said lugs of the said arm, the floor of said compartment being provided with a longitudinal guiding groove, in which the other of said lugs bears in one position of the said door, whereby as the door is opened and closed, the hinge of the door will strike and 110 rotate the said crank-shaft and cause the said arm to engage with and release from the said lever, and thereby project the said box from, and return the same to its compartment.

EZRA FLOYD AMES.
